(57) **CLAIM**

The ornamental design for a boating rack, as shown and described.

DESCRIPTION

FIG. 1 is a front perspective view of a boating rack showing my new design; and

FIG. 2 is a front perspective view thereof.

FIG. 3 is front elevation view thereof.

FIG. 4 is a rear elevation view thereof.

FIG. 5 is a side view thereof; and,

FIG. 6 is a plan view thereof.

The broken lines depict portions of the boating rack that form no part of the claimed design.
